DESIGN FOR A CLOCK CASE

Raymond K. Bevier, Avalon, Calif.

Application August 16, 1934, Serial No. 52,964

Term of patent 7 years

To all whom it may concern:

Be it known that I, RAYMOND K. BEVIER, a citizen of the United States, residing at Avalon, in the county of Los Angeles and State of California, have invented a new, original, and ornamental Design for a Clock Case, of which the following is a specification, reference being had to the accompanying drawing, forming part thereof.

Fig. 1 is a perspective view,

Fig. 2 is a rear elevation, and

Fig. 3 is a plan view of the clock case looking in the direction of the arrow as indicated in Fig. 2.

I claim:

The ornamental design for a clock case, as shown.

RAYMOND K. BEVIER.
